(57) **CLAIM**

We claim the ornamental design for a shelf nose, as shown and described.

DESCRIPTION

FIG. 1 is a top, front, right perspective view of a shelf nose showing our new design in its environment;

FIG. 2 is a top, front, right perspective view of a first embodiment of the shelf nose of FIG. 1, where a non-transparent material, as indicated by the pattern in the legend, is different from a remainder of the shelf nose;

FIG. 3 is a front elevation view of the shelf nose of FIG. 2; FIG. 4 is a back elevation view of the shelf nose of FIG. 2; FIG. 5 is a left elevation view of the shelf nose of FIG. 2; FIG. 6 is a right elevation view of the shelf nose of FIG. 2; FIG. 7 is a top plan view of the shelf nose of FIG. 2; FIG. 8 is a bottom elevation view of the shelf nose of FIG. 2;

FIG. 9 is a top, front, right perspective view of a second embodiment of the shelf nose of FIG. 1, where a metallic material, as indicated by the pattern in the legend, is different from a remainder of the shelf nose;

FIG. 10 is a front elevation view of the shelf nose of FIG. 9;

FIG. 11 is a back elevation view of the shelf nose of FIG. 9; FIG. 12 is a left elevation view of the shelf nose of FIG. 9; FIG. 13 is a right elevation view of the shelf nose of FIG. 9; FIG. 14 is a top plan view of the shelf nose of FIG. 9; FIG. 15 is a bottom elevation view of the shelf nose of FIG. 9;

FIG. 16 is a top, front, right perspective view of a third embodiment of the shelf nose of FIG. 1, where a metallic material and a white material, as indicated by the pattern in the legend, are used;

FIG. 17 is a front elevation view of the shelf nose of FIG. 16;

FIG. 18 is a back elevation view of the shelf nose of FIG. 16; FIG. 19 is a left elevation view of the shelf nose of FIG. 16; FIG. 20 is a right elevation view of the shelf nose of FIG. 16; FIG. 21 is a top plan view of the shelf nose of FIG. 16; and, FIG. 22 is a bottom elevation view of the shelf nose of FIG. 16.

The broken lines in FIGS. 1-22 are included for the purpose of illustrating portions of the shelf nose that form no part of the claimed design. The shelf nose is shown broken in one place along the length direction in FIGS. 2-4, 7-11, 14-18, and 21-22 to indicate indeterminate length, with the understanding that the “indeterminate” length portion of the shelf
